UNITED STATES PATENT OFFICE

2,493,814

AUTOMATIC CLOSURE FOR COLLAPSIBLE
TUBES

Albert E. Groody, Brooklyn, N. Y.

Application December 22, 1944, Serial No. 569,325

2 Claims. (Cl. 222—153)

1

This invention relates to self-closing tubes for use for tooth-pastes, creams and like materials.

Broadly, it is an object of my invention to provide an inexpensive closure for a flexible tube so that the material within the tube, such as tooth-paste and like materials can be easily squeezed from the tube by finger pressure and when the pressure is released, the cap will automatically close in order to prevent any of the substance within the tube from emerging from the tube.

More particularly, it is an object of my invention to provide a two piece cap for flexible tubes used for creams and the like which automatically closes upon the release of pressure.

A further object of my invention is to provide an inexpensive cap for flexible tubes which will prevent air from entering into the tube at all times so that the material within the tube will not be affected.

A further object of my invention is to provide an inexpensive cap for flexible tubes so constructed that upon manipulation of the cap, the cap will become locked to prevent any of the contents of the tube from emerging from the tube even though pressure is applied.

For a fuller understanding of the nature and objects of my invention, reference is had to the following detailed description in connection with the accompanying drawings in which:

Fig. 1 is an enlarged vertical section taken through the upper portion of the tube along line 1—1 of Fig. 2, the rest of the tube being cut away.

Fig. 2 is a top view of the tube shown in Fig. 1, part of cap portion being broken away.

Fig. 3 is a perspective view of the upper portion of the tube shown in Figs. 1 and 2.

Fig. 4 is a top view of a modified tube with part of the cap portion being partly broken away.

Fig. 5 is a vertical section of a modified cap.

Referring to the drawings, Figs. 1 to 3 inclusive, numeral 10 represents the upper portion of the tube. A lateral channel is provided at the upper portion of the tube so that movable member 12 will slidably fit within said channel. A channel 13, communicating with the lateral channel, arcuate in shape, is provided to permit spring 14 to enter channel 13 when the cap is revolved counter-clockwise. A cap 15 has a ridge 16 which seats upon a similar ridge 17 of the tube and has an opening 18 in the top 11 to permit the contents of the tube to emerge upon pressure upon the tube. The spring 14 is pressed from the material of the side 23 of the cap 15 although it may be attached to the cap by any well-known means. The upper portion of the tube has a seat 19 to

2

permit the movable member 12 to slidably move laterally thereon. Spring 14 provides a pressure upon the back 20 of the movable member 12 so that upon pressure upon the tube the contents 5 of the tube will press upon the curved face 21 of the movable member 12 and upon the curved inner portion 22 of the top of the tube thus forcing the movable member 12 rearwardly toward the side 23 against spring 14 and side 23 of the 10 cap 15 permitting the contents of the tube to emerge through the top opening 18 of the tube. Numeral 19 indicates the seat upon which the movable member 12 is seated and moves. The channel which is called a lateral channel is the 15 channel in which the movable member 12 slides, 19 being the seat of said channel. In Figure 2, it will be seen that the movable member slides reciprocably, as indicated by the double arrow and the lateral channel in which movable member 12 20 slides communicates with the arcuate channel 13. The space between the seat 19 and the tube 10 provides a lateral channel just described.

Channel 13 has a wall 24 which acts as a stop for a spring 14 when the cap is revolved.

An indent 25 is provided in cap 15 having an 25 inside face 26 which acts as a stop for the movable member 12, that is, upon turning the cap 15, the spring 14 will stop against stop 24 of the arcuate channel 13 moving indent 25 so that the 30 inside face 26 rests against the back 20 of the movable member 12, thus effectively stopping any movement of the member 12 and closing the opening 18 so that no material within the tube can emerge from the tube.

In travelling, it is always wise to turn the cap 35 in order to lock the tube so that any pressure upon the sides of the tube will not cause the contents of the tube to emerge from the tube. In filling the tube, which is usually done through 40 the bottom of the tube, the cap is turned so that it is in locked position, or when the cap is placed originally upon the tube, it may be placed in its locked position, that is, indent 25 will be directly behind movable member 12 so that in filling the tube the material will not emerge through the opening 18 of the tube. When the tube is completely filled, the bottom of the tube is then closed 45 by any well-known means.

The cap may be preferably made of metal, however, plastics and other like materials may be used and if plastics are used, of course, the spring member 14 can be attached to the plastic by eyelets or adhesive or other known means to provide pressure upon the movable member.

In the modification shown in Fig. 4, a cap 39

is provided, preferably made of plastic which can be attached to the upper portion of the tube by a ridge 27. Cap 39 has an interior projection 38 to which spring 28 may be attached by bending prongs 29 from the material of the spring itself into channels within the face of projection 38, so that spring 28 is firmly held upon ridge 38. The free end of spring 28 being in contact with the back portion of movable member 30 provides the required pressure upon such movable member. There is an opening 31 provided at the top of the cap when the movable member 30 is in retracted position to permit the contents of the tube to emerge upon pressure, as described for Figs. 1 to 3 inclusive. An arcuate channel 32 has a stop wall 33 at the end thereof so that when the cap 39 is revolved, the end 34 of the spring 28 will rest against the stop wall 33 of the channel 32, bringing the projection 38 behind the movable member 30 so that the movable member 30 is effectively locked against movement, thus closing opening 31 against emergence of the material within the tube.

Upon applying pressure to any portion of the sides of the tube, the movable member 30 will move against the spring 28 thus permitting the material to pass through opening 31. Instead of springs 14 and 28, a small rubber block may be used.

Fig. 5 is the same structure as the cap of Fig. 1 except that an interior thread 36 is used to attach cap 35 to the standard tube top 37. The same thread structure shown in Fig. 5 may be applied to the cap shown in Fig. 4.

It is obvious that various changes and modifications may be made in the details of construction without departing from the general spirit of the invention, as set forth in the appended claims.

I claim:

1. In combination with a tube, a rotatable cap having a top and a round side, means for attaching said cap to said tube, an opening in said top, a seat at the top of said tube providing a lateral channel between said seat and said top, a movable member slidably fitted within said channel, spring means within said cap for applying pressure to said movable member, an arcuate channel communicating with said lateral channel

within said cap providing a stop for limiting the rotation of said cap, a projection within said cap, said projection acting as a stop for said movable member when said projection is moved 5 behind said movable member, whereby when said filled tube is pressed the contents within said tube will cause said movable member to move against said spring pressure providing a space for the contents to emerge through said opening in 10 the top of said cap.

2. In combination with a collapsible tube, a rotatable cap having a top and a round side, means for rotatably attaching said cap to said tube, an opening in said top, a seat at the top of said tube providing a lateral channel between said seat and said top, a movable member slidably fitted within said channel, a projection on the inside of said side of said cap for seating a spring, an arcuate channel communicating with said lateral channel within said cap, said spring projecting within said arcuate channel providing resilient means against said movable member, the end of said spring acting as a stop against the end wall of said arcuate channel whereby when said cap is rotated counter-clockwise, said movable member is locked in its closed position and when said cap is rotated clockwise and the sides of said collapsible tube are pressed, the contents within said tube will cause said movable member to move against said spring to provide a space for the contents to emerge from said opening in top of said cap.

ALBERT E. GROODY.
